JOSEPH W. LEGG, DECEASED, LATE OF WILKINSBURG, PENNSYLVANIA, BY ESTHER L. LEGG, ADMINISTRATRIX, OF WORCESTER, MASSACHUSETTS; ASSIGNOR TO WESTINGHOUSE ELECTRIC AND MANUFACTURING COMPANY, A CORPORATION OF PENNSYLVANIA

HIGH-SPEED RECORDER

Application filed May 13, 1929. Serial No. 362,613.

This invention relates to recording apparatus and particularly to oscillographs which are designed to record high-speed oscillograms.

- 5   The object of this invention is to provide apparatus of the above-mentioned type for recording a large number of very high-speed oscillograms on a comparatively short length of film.
- 10   In practicing this invention there is employed a galvanometer deflecting-element and means for slowly and uniformly deflecting said element, a straight filament lamp for supplying a beam of light which is reflected
- 15   from said element to a slowly moving film, and means for passing a plurality of cylindrical lenses in rapid succession through the reflected beam of light and past the moving film.
- 20   When recording an oscillogram, the deflecting-element is vibrated in accordance with a characteristic of the quantity that is to be recorded and these vibrations are superimposed on the aforesaid slow uniform deflection.
- 25   Other features and advantages of this invention will appear from the following description taken in connection with the accompanying drawings, in which
- 30   Figure 1 is a schematic diagram of the apparatus and electrical connections employed in one embodiment of my invention.
- 35   Fig. 2 is an end elevational view of the apparatus shown in Fig. 1.
- 40   Fig. 3 is a face view of a section of film showing the arrangement of the oscillograms which are recorded by apparatus constructed in accordance with my invention.
- 45   Fig. 4 is a side view, partly in section, of the actual structure which may be employed in constructing the apparatus shown schematically in Figs. 1 and 2.
- 50   Fig. 5 is a view of the apparatus taken on the line V—V of Fig. 4.
- 55   Fig. 6 is a schematic diagram of the apparatus employed in a modification of my invention; and
- 60   Fig. 7 is an end elevational view of the apparatus shown in Fig. 6.
- 65   Referring to Figs. 1 and 2, the apparatus
- includes a galvanometer deflecting-element 1 of well-known construction which comprises two parallel conductors supported at each end and positioned within a magnetic field supplied by means of a permanent magnet 2. 55 A small mirror 3 is cemented to the conductors so that, when a beam of light 4 strikes the mirror, it is reflected to a film 5 and deflected in accordance with the current flowing through the parallel conductors. The galvanometer structure is shown in detail in my copending application Serial No. 5166, filed January 27, 1925, Patent No. 1,712,570, June 9, 1931.
- 65   The beam of light 4 is supplied by means of a straight-filament lamp 6 which is supported in a light shield 7. The light shield 7, which comprises a wall of opaque material surrounding the lamp 6, is provided to prevent rays of light from reaching the film 5 directly from the lamp.
- 70   The galvanometer element 1 and the straight-filament lamp 6 are located inside a drum 8 which is open at one end. The drum 8 is rotatably mounted by means of a shaft 75 9 which is secured to the closed end of the drum. The drum 8 may be belted to a motor (not shown) by means of a pulley 10 secured to the shaft 9.
- 75   A plurality of cylindrical condensing 80 lenses 11 are located around the periphery of the drum, each lens 11 being secured to the drum opposite a rectangular slit 12 therein. The film 5 is positioned opposite the drum 8 and provided with a supply spool 13 and a 85 take-up spool 14 by means of which the film may be slowly moved past the drum. While in the preferred embodiment of my invention the film is moved in a direction opposed to the direction of movement of the cylindrical lens adjacent to the film, it is evident that the film may be moved in the same direction as the direction of movement of the cylindrical lens so long as the film and lens do not move at the same speed. 90
- 95   The beam of light 4 is projected against the cylindrical lenses 11 and interior of the drum 8 in the form of a vertical narrow band of light. This is accomplished by placing a plano-convex spherical lens 15 (Figs. 100

4 and 5) in the wall of the galvanometer casing 16 opposite the galvanometer mirror 3 and so positioning the straight filament 17 with respect to the spherical lens 15 that 5 the image of the filament is located on or near the surface of the film 5. With such an arrangement, the light rays from the straight filament 17 pass through the spherical lens 15 to the galvanometer mirror 3 and 10 thence again through the lens 15 and to the film 5. The length of the filament image, which is approximately the width of the light band through which each cylindrical lens 11 passes, may be determined by the 15 following equation:

$$\frac{\text{length of image}}{\text{length of filament}} = \frac{\text{distance between mirror and film}}{\text{distance between mirror and filament}}$$

As each one of the cylindrical lenses 11 passes downwardly through the narrow band 20 of light, it focuses a portion of the narrow band on the moving film 5, as a moving point of light. In this way, when the deflecting-element 1 is stationary, each lens 11 traces a straight line on the film 5 as the 25 lens moves downwardly or, if the deflecting-element 1 is being vibrated, each lens 11 traces a curve on the film. It will be noted that the movement of the beam of light reflected from the vibrating deflecting-element 30 1 is at right angles to the movement of the cylindrical lenses 11 and the film 5.

The electrical quantity to be recorded may be supplied to the deflecting-element 1 through an amplifier. The amplifier comprises a three-electrode vacuum tube 18 of the usual type having a filament 19, a grid 20 and a plate 21. The filament 19 is heated by means of a battery 22 connected thereto through a rheostat 23. The filament 19 and grid 20 are connected to input terminals 24 by means of conductors 25 and 26. A "C" battery 27 is provided for putting the proper negative bias on the grid 20. A suitable potential is supplied to the plate 21 by a "B" 45 battery 28 which has its negative terminal connected to the filament 19 and its positive terminal connected to the plate 21 through a conductor 29, the deflecting element 1 and a conductor 30.

50 The circuit is so arranged that, at the time the deflecting-element 1 is being deflected by the quantity which is to be recorded, it is being slowly and uniformly deflected to move the band of light from one side of the film 55 5 to the other side. This is accomplished by means of a battery 31, one terminal of which is connected to one terminal of the deflecting element 1 through the conductors 32 and 29. The winding 33 of a potentiometer is connected across the battery 31. The rotatable contactor arm of brush 34 of the potentiometer is connected to the other terminal of the deflecting-element 1 through a variable resistance 35 and the conductor 30. During 60 the operation of the apparatus, the contact 65

arm 34 is so rotated that a varying potential is impressed across the deflecting-element 1. Accordingly, a uniformly varying current passes through the deflecting-element to cause a uniform deflection. The magnitude of this 70 deflection may be controlled by adjusting the resistance 35.

The construction of the apparatus, illustrated schematically in Figs. 1 and 2, is shown in detail in Figs. 4 and 5. The apparatus includes a light-proof casing 36 which comprises a bottom plate 37, an end wall 38, a cover 39 and a side wall 40. This part of the casing may be formed integrally from any suitable material, such as a fibre composition. 80

The other side wall of the casing 36 is removable and comprises a flanged plate 41 which may be secured to the rest of the casing by means of screws 42. The removable side wall has an opening 43 centrally located therein through which the drum shaft 9 extends. 85

The other end wall of the casing is also removable and comprises a plate 44 which may be secured to the end of the casing by means of screws 42. The end plate 44 has a rectangular opening 45 centrally located therein. 90

The drum 8 is rotatably mounted inside 95 the casing 36 and is so positioned adjacent to the removable side wall 41 and to a circular flange 46 on the side wall 40 that light is excluded from the interior of both the casing and the drum. to the horizontal. The light shield 7 and the straight-filament lamp 6 are attached to the bottom portion of the U-shaped member.

A film holder 57 is mounted on the removable end wall 44 of the casing opposite the rectangular opening 45. The film holder may be of the type described in my copending case, Serial No. 195,400, filed May 31, 1927. The inside wall of the film holder 57 has a rectangular opening therein which is in alignment with the rectangular opening 45. With the above-described arrangement, a rectangular section of film faces the interior of the casing 36 so that it may be exposed by a beam of light passing through one of the cylindrical lenses 11. The film may be driven at the proper speed by means of a pulley 58 belted to a motor (not shown).

Each condensing lens 11 is so adjusted that it will focus a portion of the band of light on the film 5 as a point of light.

To record a series of high-speed oscilloscopes, the drum 8 is rotated at high speed. At the same time, the film 5 is moved at a speed which is low as compared with the peripheral speed of the drum 8, one one-hundredth of the drum speed, for example, and the potentiometer arm 34 is rotated at a speed which preferably bears a certain fixed relation to the film speed. The quantity to be measured is impressed on the input terminals 24 of the amplifier.

Assuming the potentiometer arm 34 to be located at one end of the potentiometer resistance 33, the deflecting-element 1 will be so positioned that the band of light is projected to a position opposite one edge of the film 5, the right-hand edge of the film in Fig. 2 in the case being assumed. In Fig. 3, the top of the film is shown at the left-hand side of the figure, as indicated by the arrow.

Referring to Fig. 3, if no potential is impressed on the input terminals 24 at first, the straight line curves numbers 1, 2, 3, 4 and 5 will be recorded, each cylindrical lens 11, in succession, tracing a straight line on the film 5 as it passes through the band of light. Record number 1 has been traced by one lens. During the time that this record was being traced, the rotation of the potentiometer arm 34 caused the deflecting-element 1 to gradually shift into a different plane. Therefore, when the next lens 11 reached the upper edge of the band of light, it began tracing a curve (curve number 2) slightly to one side of the first curve. Also, during the time the first record was being traced, the film 5 had moved upward a small amount. For that reason, curve number 2 begins slightly below curve number 1. By the time the upper edge of the band of light has been reached by a cylindrical lens 11 for the sixth time in the example illustrated in Fig. 3, a variable potential has been im-

pressed on the input of the amplifier. Accordingly, the deflecting-element 1 is rapidly deflected in accordance with the variable potential to vibrate a point of light laterally with respect to the film 5. At the same time, the condensing lens 11 moves the point of light longitudinally with respect to the film 5 and a curve is traced.

As soon as the potentiometer arm 34 has completed one revolution, it again makes contact with the beginning of the potentiometer winding 33, and the deflecting-element 1 returns to its original position. The apparatus is then in condition to trace another group of curves (curves 14, 15, etc.) across the film.

The speed of the film 5 with respect to the rotating arm 34 of the potentiometer should be such that, during the time the rotating arm 34 is causing the band of light to move from the right-hand edge of the film 5 will move through a distance equal to the length of a single record. With such adjustment, when the deflecting-element 1 returns to its original position, the first record of the second group of records will begin just below curve number 1. Hence, the records will not be superimposed.

In Fig. 2, the positions of the oscilloscopes which are recorded are indicated by dotted lines. In this figure, only five oscilloscopes to a group are illustrated.

The modification of this invention which is illustrated in Figs. 6 and 7 is identical with the embodiment described above except that the cylindrical lenses 11 are positioned over radial slots 59 in a disc 60 which, like the drum 8 in the other embodiment, is made of opaque material. As shown in Fig. 7, the film 5 is positioned between the axis and the edge of the disc 60.

Various modifications may be made in this invention without departing from the spirit and scope thereof, and it is desired, therefore, that only such limitations shall be placed thereon as are shown by the prior art and set forth in the appended claims.

What is claimed as this invention:

1. In recording apparatus comprising a recording surface and mechanism for moving said recording surface, means for projecting a narrow band of light against said recording surface, a deflecting element for deflecting said band of light in accordance with the variations of an electrical quantity, means for moving said deflecting element into different planes while it is being deflected in accordance with said variations, and means for successively passing a cylindrical lens transversely through said beam, the longitudinal axis of said cylindrical lens being substantially perpendicular to the plane of said band of light.

2. Recording apparatus comprising a recording surface, means for projecting a nar-

row band of light against said recording surface, a deflecting element for deflecting said band of light in accordance with the variations of an electrical quantity, means for 5 moving said deflecting element into different planes while it is being deflected in accordance with said variations, means for successively passing a cylindrical lens transversely through said beam, the longitudinal axis of 10 said cylindrical lens being substantially perpendicular to the plane of said band of light, and means for moving said recording surface in a direction opposed to the direction of movement of said lens at a speed different 15 from the speed of said lens.

3. In recording apparatus comprising a recording surface and mechanism for moving said recording surface, means for projecting a narrow band of light against said recording surface, a deflecting element for deflecting said band of light in accordance with the variations of an electrical quantity, means for moving said deflecting element into different planes while it is being deflected in 20 accordance with said variations, and means for successively passing a plurality of cylindrical lenses transversely through said beam, the longitudinal axis of said cylindrical lenses being substantially perpendicular to 25 the plane of said band of light.

4. In recording apparatus comprising a recording surface and mechanism for moving said recording surface, means for projecting a narrow band of light against said recording surface, means for moving said band of light in a direction perpendicular to the plane of said band, means for deflecting said band in accordance with the variations of an electrical quantity during said first movement, 30 and means for successively passing a cylindrical condensing lens through said band.

5. Recording apparatus comprising a recording surface, means for projecting a narrow band of light against said recording surface, a deflecting element for deflecting said band of light in accordance with the variations of an electrical quantity, means for moving said deflecting element into different planes while it is being deflected in 45 accordance with said variations, means for successively passing a cylindrical lens transversely through said beam, the longitudinal axis of said cylindrical lens being substantially perpendicular to the plane of said band of light, and means for moving said recording surface in a direction opposed to the direction of movement of said lenses at a speed which is low compared with the speed 50 of said lens.

6. In recording apparatus comprising a recording surface and mechanism for moving said recording surface, means for passing a beam of light along a predetermined path, means for deflecting said beam of light in 55 accordance with a characteristic of a quantity

and against said recording surface, and means movable transversely of said path for focussing said beam of light substantially as a point of light for movement along the surface of said recording surface. 70

7. The combination with means for passing a beam of light along a predetermined path, of means for deflecting said beam of light in accordance with a characteristic of a quantity, a recording surface with which said beam of light coacts, means movable transversely of said path for focussing said beam of light substantially as a point of light for movement along the surface of said recording surface, and means for moving said recording surface 75 in a direction opposed to the direction of the movement of said focussing means at a speed different from the speed of said lens.

8. In recording apparatus comprising a recording surface and mechanism for moving said recording surface means for passing a beam of light along a predetermined path, means for deflecting said beam of light in accordance with a characteristic of a quantity and against said recording surface, and 80 means comprising a cylindrical lens movable transversely of said path for focussing said beam of light substantially as a point of light for movement along the surface of said recording surface. 85

9. In recording apparatus comprising a recording surface and mechanism for moving said recording surface means for passing a beam of light along a predetermined path, means for vibrating said beam of light in 90 accordance with a varying electrical quantity and against said recording surface, means for moving said beam of light across said recording surface while said beam is being vibrated in accordance with said quantity, a light shield movable transversely of said path, and a condensing lens carried by said light shield. 91

10. In recording apparatus comprising a recording surface and mechanism for moving said recording surface means for passing a beam of light along a predetermined path, means for vibrating said beam of light in accordance with a varying electrical quantity and against said recording surface, means for moving said beam of light across said recording surface while said beam is being vibrated in accordance with said quantity, a light shield movable transversely of said path, and a cylindrical condensing lens carried by said light shield. 1

11. The combination with means for passing a beam of light along a predetermined path, of means for deflecting said beam of light in accordance with a characteristic of a quantity, a recording surface with which said beam coacts, means for moving said beam of light across said recording surface while said beam is being deflected in accordance with said characteristic, a light shield 1

movable transversely of said path, a condensing lens carried by said light shield and means for moving said recording surface at such speed with respect to the speed of movement of said beam across said recording surface that said recording surface moves substantially the length of a record during the movement of said beam across said surface.

12. The combination with means for passing a beam of light along a predetermined path, of means for deflecting said beam of light in accordance with a characteristic of a quantity, a recording surface with which said beam coacts, means for moving said beam of light across said recording surface while said beam is being deflected in accordance with said characteristic, a light shield movable transversely of said path, a condensing lens carried by said light shield, and means for moving said recording surface in a direction opposite to the direction of movement of said condensing lens and at such speed with respect to the speed of movement of said beam across said recording surface that said recording surface moves at least the length of a record during the movement of said beam across said surface.

In testimony whereof, I have hereunto subscribed my name the 20th day of April, 1929.
